COMBINATION PLUG AND CAP

John W. Kort, Erie, Pa., assignor to Niagara Plastics Company, Erie, Pa., a corporation of Pennsylvania

Filed Mar. 26, 1965, Ser. No. 84,451

Term of patent 14 years

(Cl. D91—3)

FIG. 1

FIG. 2

FIG. 1 is an isometric view of a combination plug and cap, showing my new design shown plugging an open ended pipe; and

FIG. 2 is an isometric view of the cap shown in FIG. 1 shown capping a pipe.

The pipe, shown fragmentarily and in broken lines, is included for illustrative purposes only.

The characteristic features of my design reside in the generally tear-drop shape of the nubs shown on the exterior arranged in vertically oriented, substantially parallel rows as shown.

I claim:

The ornamental design for a combination plug and cap, as shown and described.
